UNITED STATES PATENT OFFICE.

ETHAN N. HESCOCK, OF WESTFIELD, NEW JERSEY, ASSIGNOR TO NEW JERSEY FOUNDRY AND MACHINE COMPANY, A CORPORATION OF NEW JERSEY.

MOTOR BRAKE FOR ELECTRIC HOISTS.

Application filed May 19, 1923. Serial No. 640,156.

To all whom it may concern:

Be it known that I, ETHAN N. HESCOCK, a citizen of the United States, residing at Westfield, in the county of Union and State 5 of New Jersey, have made certain new and useful Improvements in Motor Brakes for Electric Hoists, of which the following is a specification, taken in connection with the accompanying drawings.

10 My invention relates to an electric hoist and more particularly to one provided with a secondary or auxiliary friction brake or retarding member, to prevent the coasting or spinning of that part of the hoisting mechanism which controls the operation of 15 the first or main brake, so that the load will be held fast by the main brake, the instant that the current is cut off from the motor.

I am aware that expensive electric brakes, 20 requiring separate wiring, have been used for this purpose. By my invention the cost of an electric hoist can be greatly reduced, in that I employ a simple automatic secondary or auxiliary friction brake, and omit entirely 25 the costly electric brake and its wiring.

My invention further relates to certain combinations, sub-combinations and details of construction all of which will be more fully hereinafter described and pointed out in 30 the claims.

In the drawings I have shown one embodiment of my invention, but it is of course to be understood that my invention is not to be confined to the particular embodiments 35 shown by way of illustration.

Fig. 1 is a side elevation of an electric hoist mounted on a trolley, the I-beam track being shown in section;

Fig. 2 is a horizontal section substantially 40 on the line 2—2 of Fig. 1 and on an enlarged scale;

Fig. 3 is a vertical section taken on the line 3—3 of Fig. 2.

Fig. 4 is a detail view.

45 In the particular form of electric hoist that I have shown, by way of example, the entire electric hoist mechanism 1 is mounted upon the trolley 2 carried by the rollers 3, 3 supported by the I-beam track 4. While

50 I have, for purpose of illustration, shown the electric hoist movable on a trolley it is, of course, to be understood that it may be fixed if desired.

55 This electric hoist is provided with the usual control box 5, switch 6, control cord

7, motor 8, and main axle 9. From the main axle 9 to the winding drum suitable reducing gear is employed. I have shown, for example, the main axle 9 extending entirely through the main housing 10 and into the 60 supplemental housing 11. Keyed to the main axle 9 is a pinion 12 in mesh with the gear wheel 13 keyed upon a counter shaft 14. On this counter shaft is also keyed a pinion 15 in mesh with the gear wheel 16 which in 65 turn is keyed to the sleeve 17 of the pinion 18 loosely mounted upon the main axle 9. This pinion 18 is in gear with the gear wheel 19, keyed on the sleeve 20 of the friction disc 21. This disc 21 is provided with 70 female screw-threads to cooperate with the male threads 22 upon the counter-shaft 23. Upon this counter-shaft is keyed a check-washer 24, having a tooth 25 normally in 75 engagement with a tooth 26 on the friction disk 21. The arrangement is such that the relative rotation of the friction disk 21 and its sleeve 20, with relation to the counter-shaft 23, is limited to one rotation to permit the tooth 26 to engage on either side of the 80 tooth 25 carried by the check-washer 24 keyed on the counter-shaft 23. Mounted loosely upon the same counter-shaft 23 is another friction disk 27. A pinion 28 is keyed 85 upon the shaft 23.

Between the friction disks 21 and 27 is mounted the main brake wheel 29 free to rotate in one direction. Its periphery is provided with teeth 30 to cooperate with the fixed pawl 31 mounted on the pin 32, carried by the housing 10. Between the brake wheel 29 and the friction discs 21 and 27 I preferably mount loose friction members of 90 any suitable material 33, 33.

In mesh with the pinion 28 is a gear 95 wheel 34 which is loosely mounted upon the hollow sleeve shaft 35. This gear wheel 34 is provided with a sleeve 36 having arms 37, 37 to cooperate with enlarged pockets or recesses 38, 38 (only one being shown in 100 Fig. 2) in the winding drum 39, which is itself loosely mounted upon the hollow sleeve shaft 35.

From the mechanism so far described, when it is desired to raise a load connected 105 to the hook 40, Fig. 1, so as to wind the rope or cable 41 upon the winding drum 39, the switch 6 of the control box 5 is operated, in any suitable manner as for example by the cord 7, so as to energize the motor 8 110

and operate the main shaft 9. Power is transmitted from this main shaft 9 to pinion 12, gear wheel 13 mounted upon the counter-shaft 14, counter-shaft 14, pinion 15 keyed 5 upon said counter-shaft, gear wheel 16, loose pinion 18, gear wheel 19, friction disc 21, and counter-shaft 23. The screw-threads between the friction disc 21 and the counter-shaft 23 cause the friction disc 21 to move laterally, or to the left of Fig. 2, and firmly 10 grip the brake wheel 29 between the friction disc 21 and the friction disc 27, thereby causing the main brake wheel 29 to rotate with the friction discs 21, 27 and counter-shaft 23, the fixed pawl 31 idly engaging the teeth 30 on the periphery of the brake wheel as it is moved under said pawl. The power is then transmitted through the pinion 28 fast on counter-shaft 23 to the gear wheel 15 20 34, loosely mounted upon the hollow sleeve shaft 35, and to the winding drum 39, to wind up the rope chain or cable 41 so as to lift the hook 40 and any load that may be attached to it.

25 In this operation of raising the load, the main shaft 9 operates counter-clockwise, and the counter-shaft 14 operates clockwise, as indicated by the arrows, Figs. 2 and 3.

When it is desired to lower the load, the 30 current is reversed through the motor 8 and the main shaft 9 is reversed and made to revolve clockwise and the counter-shaft 14 counter-clockwise. This reversing of the current and of the main axle 9 causes the 35 friction disc 21 to move slightly on its screw-thread on the counter-shaft 23 so as to free the brake wheel 29 of the grip of the two friction disks 21 and 27 and of the friction members 33, 33, if they are employed. During this lowering or retrograde 40 movement of the hook 40 and its load, the brake wheel 29 is held immovable by means of the fixed pawl 31 engaging with one of the teeth 30. Theoretically it is possible 45 to lower the load and stop it at any desired elevation by simply cutting off the current from the motor 8 so that the brake disks 21 and 27 would instantly again clamp and hold the brake wheel 29, which is held by 50 the fixed pawl 31, so that further downward movement of the load, after the current is cut off, would be impossible.

55 It is found in practice, however, that this is not so, for the reason that after the current is cut off the motor, the main axle 9 and the reducing gear connected therewith, will spin or coast and prevent the instant gripping of the brake wheel 29 by the friction disks 21 and 27. The result is that 60 such electric hoisting mechanism is unsatisfactory in practice unless this spinning or coasting of the main axle 9, and its connected gearing, is stopped instantly as soon as the current is cut off the motor, for otherwise, the main brake mechanism, previously

described, will not hold the load at any fixed or determined point, but will permit the load to drift downward beyond the point desired by the operator to a greater or less 70 distance.

To overcome this difficulty, very expensive electric brake mechanism have been employed to stop the coasting or spinning of the main axle 9. Not only is it necessary, in such devices, to use such an expensive electric 75 brake, which, of course, adds materially to the cost of the electric hoist, but in addition thereto, extra wiring for the electric brake has to be employed.

80 My invention relates primarily to substituting for such an expensive electric brake a simple, efficient and automatic friction brake, which, of course, requires no additional wiring, and which can be added to the electric hoist mechanism at minimum 85 expense.

90 In the embodiment of my invention shown in the drawings, I employ my friction brake to act directly upon the main axle 9, or a secondary or auxiliary brake wheel keyed to 95 said axle. In the particular form of my invention shown the application of the secondary or auxiliary brake is controlled by the direction of rotation of the counter-shaft 14.

95 Within the secondary housing 11, which is connected to the main housing 10, I key a brake wheel 46 to the main axle 9. Around the end of the counter-shaft 14 I mount the clamps 47 and 48, these clamps bearing 100 more or less upon the counter-shaft 14 by means of the bolts 49, 49, springs 50, 50 and nuts 51, 51, which adjust the friction of said clamp upon the rotating counter-shaft 14. These clamps 47, 48 are provided 105 with jaws 52, 52 to receive between them the lug 53 secured on the end of the band brake 54, the other end of which is secured to the pin 55, carried by the fixed housing 10.

110 In winding the rope, cable or chain 41 upon the winding drum 39, to raise a load attached to the hook 40, the main axle 9 rotates counter-clockwise, and the counter-shaft 14 operates clockwise as shown by the arrows in Fig. 3. This will cause the clamps 47, 48 to move the lug 53 and with it the 115 band brake 54 away from the secondary or auxiliary brake wheel 46, so that in raising a load there will be no friction or drag upon the main shaft 9. In lowering a load, by reversing the direction of rotation of the 120 main shaft 9 and the counter-shaft 14, the spinning or coasting of the main shaft 9 is instantly prevented for the reason that the counter-shaft 14 would then be rotating counter-clockwise and would cause the 125 clamping jaws 52 and 53 to move counter-clockwise and bring the band brake 54 firmly against the auxiliary or secondary brake wheel 46 then rotating clockwise. This will 130 instantly stop the spinning or coasting of

the main axle 9, thereby permitting the load to operate the main brake, previously described at length, which will hold the load at the point or location where the current 5 is cut off the motor and prevent it drifting downward, more or less, beyond the point desired by the operator. It is, of course, to be understood that the coasting of the main axle 9, after the current is cut off, prevents the immediate application or relative movement of the screw-threads 22 cooperating with the female screw-threads in the friction disk 21 to instantly lock the main 10 brake and hold the load.

15 When it is desired to lower the hook 40, this can be readily done by reversing the motor and the shaft 9, my secondary brake mechanism not interfering with the free movement of the hook 40 and cable 41.

20 In operating the electric hoist the motor is energized to raise the load and theoretically it would be possible to hold the load at any desired elevation by simply cutting off the current from the motor. Due to the 25 coasting of the main axle 9 and the reducing gear it is found in practice that the main brake mechanism will not hold the load at any fixed or determined point, but on the contrary, will permit the load to drop, 30 more or less, beyond the point desired by the operator.

The secondary automatic brake 54 does not engage with the secondary brake wheel 46 as long as the load is being raised because, at that time, the rotation of the countershaft 14 (Fig. 3) is clockwise, as shown 35 by the arrow. As soon as the current is cut off the motor and the load starts, even so slightly, to descend, or try to descend, 40 beyond the desired point to which it has been raised, the countershaft 14 will be moved slightly counterclockwise in the reverse direction from the arrow (Fig. 3), and instantly and automatically will actuate the 45 brake band 54 bringing it into engagement with the secondary brake wheel 46 keyed to the shaft 9, thereby instantly stopping the spinning or coasting of the main axle 9 and the gearing, permitting the main brake 50 to function and hold the load at the desired elevation.

It is, of course, understood that the motor actuates the shaft 9 both on raising or lowering a load attached to the hook 40. The 55 secondary brake 54 is only actuated to stop the spinning or coasting of the main axle 9, and the gearing, when the current is cut off, to hold the load at any given elevation.

On raising a load the brake 54 does not 60 contact with the brake wheel 46, so that the load is raised free of any retarding effect of this brake.

In lowering the hook 40 with its load, the direction of rotation of the counter 65 shaft 14 is such that the brake band 54 is

brought into engagement with the auxiliary brake wheel 46, but its retarding effect, against the action of the motor in reverse and the weight of the load is negligible. Its function is not to hold the load or materially retard the motor in reverse on lowering the load, but to stop the spinning of the axle 9 with its gears, so that the main holding brake 29, with its cooperating parts, will immediately function to itself hold the 70 load at any desired elevation, as soon as the motor is cut off.

Having thus described this invention in connection with an illustrative embodiment thereof, to the details of which I do not desire to be limited, what is claimed as new and what is desired to secure by Letters Patent is set forth in the appended claims.

What I claim is:—

1. In a hoist mechanism the combination 85 of a power shaft, means to operate it to raise a load, two friction brakes, one to hold the load and the other controlling the actuating member of the first friction brake.

2. In an electric hoist mechanism including a main shaft, two friction brakes, one adapted to hold the load and the other friction brake cooperating with the main shaft to prevent coasting or spinning of that shaft after the current is cut off the motor. 90

3. In an electric hoist mechanism including a main shaft, the combination of a main brake to hold the load, a counter-shaft, a secondary or auxiliary brake to prevent the coasting or spinning of the main shaft, said 100 secondary or auxiliary brake being operated by the counter-shaft.

4. In an electric hoist mechanism including a main shaft, the combination of a main brake to hold the load, a counter-shaft rotating in a different direction from the main shaft, a secondary or auxiliary brake to prevent the coasting or spinning of the main shaft, said secondary or auxiliary brake being automatically operated by the 105 counter-shaft.

5. In an electric hoist mechanism including a main shaft, the combination of a main brake to hold the load, a brake wheel mounted on the main shaft, a counter-shaft, a secondary or auxiliary brake member to cooperate with the brake wheel on the main shaft, said secondary or auxiliary brake member being operated by the counter-shaft. 115

6. In an electric hoist mechanism including a main shaft, the combination of a main brake to hold the load, a brake wheel mounted on the main shaft, a counter-shaft, a secondary or auxiliary brake band adapted to cooperate with the brake wheel and a member on the counter-shaft to automatically operate the brake band. 120

7. In an electric hoist mechanism including a main shaft, the combination of a main 130

brake to hold the load, a brake wheel mounted on the main shaft, a counter-shaft, a secondary or auxiliary brake band to cooperate with the brake wheel and a clamp on the counter-shaft to automatically operate the brake band.

8. In an electric hoist mechanism including a main shaft, the combination of a main brake to hold the load, a brake wheel mounted

ed on the main shaft, a counter-shaft, a secondary or auxiliary brake band to cooperate with the brake wheel and an adjustable clamp on the counter-shaft to automatically operate the brake band. 10
